FRONT SETTING MEANS FOR CLOCKS

Edgar Bourquin, Los Angeles, Calif.

Application June 27, 1947, Serial No. 757,392

5 Claims. (Cl. 58—80)

1

My invention relates to electrically driven clocks and is particularly directed to an arrangement and combination of elements whereby the minute and hour hands of the clock may be adjusted, the minute and hour hands and an alarm-setting hand may be selectively and individually adjusted, two separate alarms may be selectively and individually adjusted, a seconds indicator may be adjusted, or a seconds indicator and the minute and hour hands may be selectively adjusted, in each case from the dial face or front of the clock.

This application is a continuation-in-part of my parent, co-pending application Serial No. 610,445, filed August 13, 1945, issued as United States Letters Patent 2,562,293 on July 31, 1951, which patent discloses but does not claim a front setting electric clock construction of the type herein described and claimed, and, in addition, discloses and claims frontally arranged alarm shut-off means.

Electrically operated clocks ordinarily contain a case in which the motor and gearing are contained. In the event the clock is of the alarm or signaling type, it is usually provided with a setting hand which appears on the dial face with its center of rotation removed from the axis around which the minute and hour hands rotate. Means for presetting the alarm and means for adjusting the hour and minute hands, as well as means for rendering the signaling device either operative or inoperative, are generally located on the back of the clock case and extend rearwardly therefrom so that all of the adjustments are made from the rear. No difficulty is encountered in making such adjustments in the event the clock is of the so-called "desk" type where it is supported from a table, clock shelf, or the like, and ready access is had to the rear of the clock case. However, there are many instances where it is desirable to have the clock positioned within a recess or fastened to a wall or panel so that the dial face is virtually flush with the surface of the wall or panel. In such instances, access to the rear of the case is virtually impossible.

The present invention permits electric clocks to be mounted within a panel, wall, or other supporting structure and all of the necessary adjustments may be readily made from the front of the clock.

In a clock having two separate alarms the above argument is also true, since the adjusting and setting means in prior art clocks would be at the back thereof, thus rendering it impossible to mount said clocks in a panel or wall mounting where the back thereof is inaccessible. The pres-

2

ent invention permits electric clocks to be mounted within a panel, wall, or other supporting structure and each alarm selectively, individually adjusted from the front or dial face of the clock.

5 Prior art clocks provide no means for adjusting the seconds hand. Therefore, such clocks may be inaccurate within a plus or minus range of up to sixty seconds and it is highly desirable that means be provided for adjusting the seconds hand or other indicator to the correct time. The present invention permits such adjustment of a seconds indicator from the dial face or front of the clock which may be mounted within a panel, wall, or other supporting structure.

10 Furthermore, the present invention provides means whereby an adjustable seconds indicator may selectively engage the minute and hour hands of the clock for adjusting the same from the dial face or front of the clock.

15 20 With the above points in mind, it is an object of the present invention to disclose and provide an electric clock provided with means for setting the minute and hour hands from the face thereof.

25 30 A further object of the invention is to disclose and provide an electrically driven alarm clock, including an alarm-setting hand, both the alarm-setting hand and the time-indicating hands being capable of adjustment from the front of the clock.

35 40 It is a further object of this invention to disclose and provide an electrically driven alarm clock, including two alarm mechanisms and two alarm-setting hands, both of the alarm-setting hands being capable of selective, individual adjustment from the front of the clock.

45 It is a further object of this invention to disclose and provide an electric clock including a seconds indicator capable of adjustment from the front of the clock.

50 It is a further object of the present invention to disclose and provide an electric clock provided with a seconds indicator capable of adjustment from the front of the clock and also selectively arranged for adjustment of the minute and hour hands from the front of the clock.

Other and allied objects of this invention will become apparent to those skilled in the art from the following description of exemplary constructions by means of which the desired objects may be attained and by a careful study of the illustrations, specification and appended claims. To facilitate understanding, reference will be had to the following drawings of various illustrative embodiments of the invention, in which:

Fig. 1 is a front elevation of a clock constructed in accordance with the present invention set into or mounted upon a panel or wall. (This figure is identical to Fig. 1 of the before-mentioned parent application Serial No. 610,445, filed August 13, 1945, now Patent No. 2,562,293.)

Fig. 2 is a front elevation of the clock with the motor, clock works, and dial face removed. (This figure is identical to Fig. 2 of the before-mentioned parent application.)

Fig. 3 is a horizontal section taken along the plane III—III of Fig. 1. (This figure is identical to Fig. 3 of the before-mentioned parent application.)

Fig. 4 is a vertical section taken along plane IV—IV of Fig. 1. (This figure is identical to Fig. 4 of the before-mentioned parent application.)

Fig. 5 is a fragmentary, horizontal section of a second illustrative form of the invention, partially broken away and with certain portions removed for clarity.

Fig. 6 is a fragmentary, horizontal section of a third illustrative form of the invention, partially broken away and with certain portions removed for clarity.

Fig. 7 is a vertical section of one illustrative form of manually adjustable front setting means.

Fig. 8 is a partial vertical section of a modified illustrative form of manually adjustable front setting means.

Fig. 9 is a vertical section of an illustrative form of front seconds setting means.

The clock shown in Figs. 1 to 4 inclusive is of rectangular shape and comprises a case 1 inserted into a recess formed in the wall or panel 2. Any suitable means may be used in positioning and holding the clock within the panel. The case 1 may be imperforate except for a port 3 through which the normal, electrical conductor 4 is passed for the purpose of supplying the clock with power. The clock includes the dial face 5 carrying suitably arranged indices to indicate the hours, the minute hand being indicated at 6 and the hour hand indicated at 7. Circularly arranged around the central axis of rotation of the minute and hour hands is a series of indices for indicating the time for which the alarm is preset and a setting hand 8, rotatable about the main axis of the minute and hour hands, cooperates with these additional, circularly arranged indices. The clock face may also be provided with a cover or crystal 9 held against the dial and attached to the case as by means of a bezel 10.

Positioned within the clock case 1 is a magnetic core 11 having a field coil 12 wound around one portion thereof, the ends of the field coil being connected to the electrical leads leading from a source of power. The magnetic core 11 forms a gap 13 adapted to receive the rotor of a suitable electric motor whose housing is indicated at 14. Details of the motor need not be shown, since they are well known in the art. Such motor ordinarily includes a driving pinion 15 extending therefrom, the pinion cooperating with suitable clock works for actuating the minute and hour hands.

In the drawing, the clock works are shown contained and carried by a front plate 16 and a rear plate 17, the two plates being maintained in suitable, spaced relation by means of spacers, one of which is indicated at 18. The entire clock works assembly may be removably attached to the rear wall of the case 1 as by means of stud bolts or spacers 19.

In the event the clock is of the alarm type, a

vibratable armature or striker 20 is positioned within the case, one end of the striker being attached to the case as at 21. When such striker 20 is released, it will vibrate either against the core 11 or against a suitable bell or sounding element (not shown).

An axially movable shaft or pin 24 is journaled in the rear plate 17 of the clock works and is provided with an alarm setting gear 25 mounted upon the end of the shaft 24. The shaft or pin 24 is surrounded by a sleeve 26 carrying the minute hand 6. Rotatably mounted upon the sleeve 26 is an hour sleeve 27 carrying the hour hand 7. Rotatably surrounding the hour sleeve 27 is an alarm-setting sleeve 28 carrying the setting hand 8. The setting sleeve 28 is journaled in the front plate 16 of the clock works.

The minute hand of the clock is driven in the following manner. The pinion 15 drives a gear and pinion assembly 30 journaled upon the stem 24. The pinion portion of such assembly is in driving engagement with a gear 31 (see Fig. 4) associated with a pinion 32 journaled upon a stub shaft 33. The pinion 32 is in operative engagement with a gear 34. The last-mentioned gear 34, as well as its associated pinion 35, is carried by the minute-hand sleeve 26.

The hour hand 7 and its associated sleeve 27 are driven as follows. The pinion 35 (carried by the minute sleeve 26) drives gear 36 and its associated pinion 37, the pinion being in engagement with the gear 38 which is carried, together with its pinion 39, upon the hour sleeve 27.

The forward or front end of shaft 24 carries a collar 40 provided with an actuating knob, the collar and knob extending through a suitable port in the cover glass 9. It will be evident that rotation of the collar and knob will be translated by gear 25 to rotation of the gear 41 mounted upon the stub shaft 42, this shaft carrying a gear 43 which is in engagement with a gear 44 mounted upon the setting sleeve 28 carrying the setting index arm 8. Concurrently with the movement of setting hand 8, movement is imparted to a signal setting gear 45 journaled upon stub shaft 46 (Fig. 3) inasmuch as gear 45 is in engagement with the gear 44. The signal setting gear 45 is provided with an opening, slot or port 47 adapted to receive a signal pin carried by gear 48, this gear being driven by pinion 39 attached to the hour sleeve 27. The gear 48 is slidably upon the stub shaft 46 and yieldably urged against the signal setting gear 45 by means of a spring-actuated member 49, whose other end, not shown, carries a member extending beneath the striker arm 20 normally preventing such striker arm from vibrating. In the event the signal pin enters the slot or opening 47, such member releases the striker 20. Details of this member are not shown, since they are well known in the art.

It will be noted that normally the shaft 24 is yieldably urged toward the front of the device by means of a spring 52 carried by the rear plate 17 of the clock works so that the gear 25 is in constant engagement with gear 41. If it is desired to change the setting of the minute and hour hands of the clock without changing the setting of the alarm indicator 8, the shaft 24 is moved axially toward the rear of the case by pressing upon the collar and knob 40, thereby moving the gear 25 out of engagement with the gear 41. Clutch means are provided between the end of minute-hand sleeve 26 and the collar 40, opposing ends of the sleeve and collar being serrated or toothed. It will be evident that when

axial movement is imparted to the shaft 24 by pressing upon the collar and knob 40, driving engagement is made between the collar 40 and the minute-hand sleeve 26 so that rotation of the collar 40 will cause rotation of the minute hand 6. Manual rotation of the sleeve 26 will, by means of the gearing hereinbefore described, cause a corresponding rotation of the hour-hand sleeve 27. When the axially directed pressure is released, the spring 52 returns the shaft 24 to its normal position, as shown in Fig. 3.

From the description given hereinabove, it will be evident that front setting means have been provided for adjusting the time-indicating hands and selectively positioning the alarm-setting hand 8. Means have also been provided to render the alarm or striker 20 either operative or inoperative, that is to inhibit the alarm or shut it off, or to place it in a condition where it will become energized at a time indicated by the setting hand 8. Such means comprise a lever 55 pivotally connected as at 56 to a bracket 57 extending from the rear plate 17 of the clock works. The lever 55 carries a latch 58 capable of being moved into engagement with the striker 20 so as to prevent its vibration. In Fig. 4, the latch 58 is in a disengaged position with respect to the striker 20.

Rods 60 and 61 extend through the front and rear plates of the clock works and through the dial 5 so as to be accessible from the front of the clock. The front end of rod 60 may carry a push plate 60' marked "On," whereas the front end of rod 61 may carry a push plate 61' marked "Off." The ends of lever 55 may be provided with horizontally extending extensions 55' and 55'', terminating in upwardly extending pins capable of engaging slots formed in the inner arms of rods 60 and 61. It will be evident that manual movement of the rods pivots the lever 55 so as to cause the latch 58 to selectively engage and disengage the striker arm 20. In order to shut off the alarm, it is necessary only to push the protruding end 61' of the rod 61.

As a result, all of the desired settings and adjustments may be accomplished from the front of the clock without the necessity of removing the clock from its position in the wall or panel 2 and without touching the rear of the case.

Fig. 5 is a fragmentary horizontal section of a second illustrative form of the invention, partially broken away with the driving motor and certain gearing driven thereby, and the spring-actuated member which controls the striker arm of the alarm, similar to that shown in Figs. 3 and 4, removed for clarity. The general construction is quite similar to that shown in the first form of my invention illustrated in Figs. 1 through 4 inclusive, with certain modifications. Referring to said Fig. 5, an axially movable shaft 100 is journaled in the front plate 101 and the back plate 102 in a manner similar to that hereinabove described. A minute-hand sleeve 103 is journaled on the shaft 100. An hour-hand sleeve 104 is journaled on sleeve 103. The outer end of the minute-hand sleeve 103 carries a minute hand 105 and the outer end of the hour-hand sleeve 104 carries an hour-hand 106, said hour and minute hands being positioned in front of a dial face 123 which may carry suitable time-indicating indices.

The outer end of the shaft 100 carries frontally extending means, in this case a manual adjusting knob 107 which is adapted to assume either of two positions, the one shown in solid lines being

the normal position thereof and the one shown in dashed lines being axially shifted position thereof when the knob 107 is manually grasped and pulled so as to longitudinally, axially shift said knob 107 and shaft 100 into shifted position. The purpose of this shifting operation will be disclosed hereinafter.

It should be noted that while, in the example shown, the clock crystal is centrally perforated at 109 and the knob 107 extends therethrough so as to be manually accessible externally of said crystal 108, this construction is purely optional and the knob 107 may be positioned within the crystal or cover 108 and access thereto provided, by hingedly connecting the crystal at one side thereof for opening same, or by any other suitable means.

Fixed to the minute-hand sleeve 103 adjacent the rearward end thereof is a gear 110 and a pinion 111, these being adapted to form part of the reduction gearing drive which is operably connected to suitable driving means, not shown, and function in a manner similar to gear 34 and pinion 35 shown in Figs. 3 and 4 of the first form of this invention. This is not illustrated fully since it is shown in Figs. 3 and 4 and is well known in the art. Immediately forward of the gear 110 and pinion 111, a gear 112 and a pinion 113 are affixed to the rearward end of the hour-hand sleeve 104 and also form part of the reduction gearing drive adapted to cooperate with suitable driving means, not shown, and function in a manner similar to gear 38 and pinion 39 shown in Figs. 3 and 4. This is not shown fully since it is illustrated in Figs. 3 and 4 and is also known in the art.

The inner end of the minute-hand sleeve 103 is provided with circularly arranged clutch teeth 114 on the end thereof. A pinion 115, fixed to the shaft 100 slightly spaced from and adjacent the teeth 114, is provided with a second set of clutch teeth 116 facing the clutch teeth 114 and adapted to cooperate therewith upon axial shifting of the shaft 100 in response to manual gripping of the knob 107 and pulling same to the position shown in dashed lines. This effectively engages teeth 116 and 114, thus operatively engaging the knob 107 with minute-hand sleeve 103 carrying minute hand 105, whereby rotation of said knob will impart rotation to minute hand 105 and through the gearing transmit rotation to the hour-hand sleeve 104 and hour-hand 106, for adjusting and setting said minute and hour-hands while the knob 107 and shaft 100 are in said axially shifted position.

A bracket 99 may be affixed to the rear plate 102 and arranged to maintain the minute-hand sleeve in a forward position so that the clutch teeth 114 normally will be out of contact with the clutch teeth 116.

Normally, the knob 107 carried by the shaft 100 and the pinion 115 fixed to said shaft are held in the position shown in Fig. 5 by a biasing spring 117. In this position the pinion 115 is in engagement with an alarm-setting gear 118 fixed upon a stub shaft 119, which is rotatably mounted in the front and rear plates 101 and 102 off-set from the centrally disposed shaft 100. Suitable friction means, indicated at 120, fixed upon the stub shaft 119, is in spring-pressed, frictional engagement with the inner side of the rear plate 102 by reason of the action of a lateral spring 121 carried by the rear end of the stub shaft 119 and pressing forwardly against the rear surface of plate 102, tending to force the friction means

120 against the front side of plate 102 into frictional contact therewith, thus causing the alarm-setting gear 118 to maintain whatever position it is set to. In said normal position, as shown in solid lines in Fig. 5, rotation of the knob 107 will cause a rotation of the alarm-setting gear 118 and also a corresponding rotation of the alarm-setting or indicating hand 122 carried by the forward end of said stub shaft 119 in front of the dial face 123, which may be provided with suitable indicating indices arranged around the axis of the stub shaft 119 on the dial face 123.

Slidably rotatably mounted on the stub shaft 119 forward of the alarm-setting gear 118 is element 124 which has provided thereon a pin 125 normally in spring-pressed contact with the front side of gear 118 and adapted to fall into and engage a hole 126 in gear 118 when in alignment therewith, under the backward spring-biasing action of a spring 127 positioned between the front plate 101 and a driven gear 128 fixed to the forward end of the element 124. The gear 128 is in engagement with the pinion 113 on the hour-hand sleeve 104 and is driven thereby, which rotates the pin 125 until it is in alignment with the hole 126 in the alarm-setting gear 118, which then allows the entire element 124 and gear 128 to axially slide backward on the stub shaft 119 until the projection 125 is within the hole 126 in the alarm-setting gear 118. This takes place at the time indicated by the alarm-setting hand 122, as adjusted in a manner hereinbefore described by the knob 107.

An alarm striker detent adapted to suppress action of an alarm striker at times other than when the projection 125 is within the hole 126, and similar to that shown at 49 in the first form of my invention (Fig. 3) may engage the face of the axially movable gear 128 for releasing the alarm striker when the pin 125 falls into the corresponding hole 126 in the alarm-setting gear 118 in a manner similar to that described and illustrated in the first form of my invention. This alarm striker detent, alarm striker, and alarm are not shown, since they are illustrated in Figs. 3 and 4.

Fig. 6 is a fragmentary, horizontal section of a third illustrative form of the invention, partially broken away and with the driving motor, portions of the associated gearing, and the alarms removed for clarity, and is a slightly modified form of the construction shown in Fig. 5. The parts corresponding to those shown in Fig. 5 are given corresponding primed reference numerals. New elements are given new reference numerals.

The construction shown in Fig. 6 is the same as that shown in Fig. 5 with the following exceptions. The rear end of the minute-hand sleeve 103' has no clutch teeth thereon such as the clutch teeth 114 shown in Fig. 5. The forward end of the pinion 115' similarly has no clutch teeth thereon such as the clutch teeth 116 shown in Fig. 5. Therefore, axial movement of the shaft 100' from the position shown in solid lines to the position shown in dashed lines does not cause engagement of the pinion 115' and the minute-hand sleeve 103', as in the form of my invention illustrated in Fig. 5. However, a second offset stub shaft 129 is rotatably mounted in the front and back plates 101' and 102'. This stub shaft 129 extends through the rear plate 102' and has a laterally arranged spring 130 pressing against the rear surface of the rear plate 102' so as to bias the stub shaft 129 in a rearward direction.

Fixed to the stub shaft 129 immediately forward of the rear plate 102' is a friction element 131 and an alarm-setting gear 132. It should be noted that the lateral spring 130 normally causes the friction element 131 to frictionally engage the forward face of the rear plate 102'. The stub shaft 129 also slidably and rotatably carries an element 133 provided with a projection 134 thereon normally in spring-pressed engagement with the front face of the gear 132 and adapted to fall into and engage a hole 135 therein when in alignment therewith. The forward end of the element 124 has affixed thereto a gear 136 which engages the pinion 113' fixed to the hour-hand sleeve 104' for driving said gear 136 and the element 124 connected thereto. A coil compression spring 138 is positioned between the forward face of the gear 136 and the rear face of the forward plate 101' for normally biasing the gear 136 and element 133 rearwardly. The forward end of the stub shaft 129 extends through the front plate 101' and the dial face 123' and carries an alarm-indicating and setting hand 137 which cooperates with suitable alarm-setting indices arranged on the dial face 123' around the axis of the stub shaft 129.

It will be noted that the structure described in the paragraph immediately above is a duplicate of the stub shaft 119, element 124', projection 125', alarm-setting gear 118', lateral spring 121', driven gear 128', compression spring 127' and alarm-setting or indicating hand 122'. In other words, two separate alarm-setting and alarm set-off arrangements are disclosed in Fig. 6. It should be noted that the alarm-setting gear 132 is in a plane just forward of the engaging plane of the pinion 115' when in the position shown in solid lines in Fig. 6 when said pinion 115' is in engagement with the other alarm-setting gear 118' for setting the other alarm on the opposite side of the shaft 100'. When the knob 107' is manually grasped and pulled into the position shown in dashed lines, longitudinally axially moving the shaft 100', the pinion 115' moves out of engagement with the first alarm-setting gear 118' and into engagement with the second alarm-setting gear 132, whereby rotation of the knob 107' in said axially shifted position will rotate said alarm-setting gear 132 and the alarm-setting or indicating hand 137 to a selected position. The pinion 113' driven by the hour-hand sleeve 104' drives the gear 136 and the element 133 attached thereto, rotating the projection 134 until it is in alignment with the hole 135 in the alarm-setting gear 132, whereupon said projection 134 falls into and engages said hole 135, axially moving the element 133 and the gear 136 along the stub shaft 129 under the action of the coil compression spring 138.

An alarm striker detent similar to that shown at 49 in Fig. 3 illustrating the first form of my invention, and arranged to normally restrain an alarm striker from actuating an alarm may be placed in contact with the gear 136 and arranged to release the alarm striker for allowing actuation of the alarm when the projection 134 becomes aligned with the hole 135 and falls into and engages said hole, thus allowing the element 133 and the gear 136 to axially slide rearwardly on the shaft 129 under the force exerted by biasing coil compression spring 138. This alarm striker detent, alarm striker, and alarm are not shown herein, since they are illustrated in the first form of my invention in Figs. 3 and 4.

It is to be noted that two separate, individual, alarm striker detents, striker arms and alarms are utilized in the form of my invention illustrated in Fig. 6, either of said alarms being selectively presettable from the front or dial face of the clock by rotation of the knob 107 in either of the axial positions it may assume. (In Fig. 6 one of said positions is shown in solid lines and the other of said positions is shown in dashed lines.) Means may also be provided for adjusting the minute and hour hands.

Fig. 7 is a vertical section of one illustrative form of manually adjustable, front setting means, with the balance of the clock broken away. In such figure, the centrally disposed shaft 139, which, in the example illustrated, may be a driven seconds-indicating shaft, has concentrically journaled thereon a minute-hand sleeve 140 and an hour-hand sleeve 141. The seconds shaft 139 may be an extension of a motor output shaft revolving at one revolution per minute. The shaft 139 may carry a pinion engaged with a gear carried by a countershaft extending parallel to the seconds shaft. Suitable gear means may be carried by the countershaft for engagement with cooperative pinions carried by the minute-hand and hour-hand sleeves. A hub 142 is fixed on the left hand, outer end of the hour-hand sleeve 141 and is provided with an hour-hand 143 thereon. A hub 144 is fixed to the lefthand, outer end of the minute-hand sleeve 140 and is provided with a minute hand thereon. The shaft 139 extends forwardly beyond the hour and minute hands 143 and 145 and is provided with an end hole 146 therein and annular groove 147 immediately behind the end hole 146.

A frontally extending means, in this case a seconds-indicating knob 148, is provided with a centrally apertured hub 149 therein adapted to slide over the outer end of the shaft 139 with a coil compression spring 150 positioned in the end hole 146 in the shaft 139 and abutting the inner surface of the knob 148. The hub 149 is provided with a flat spring 151 along one surface thereof and with a recess 152 under said spring 151 adjacent the end of the hub 149. A ball bearing 153 may be positioned in the recess 152 and spring-biased by spring 151 into contact with the annular groove 147 in the shaft 139. The coil compression spring 150 causes the ball bearing 153 to also be forced against the forward shoulder forming the annular groove 147 in the shaft 139. Thus, the spring 151, ball bearing 153, groove 147, and spring 150 cooperate to maintain the frontally extending means 148 in rotatable, axially movable, spring-biased, frictional relationship on the outer end of the shaft 139. The rear end of the hub 149 is provided with clutch teeth 154 arranged to cooperate with similar clutch teeth 155 which may be on the forward end of the minute-hand hub 144 or the forward end of the minute-hand sleeve 140. Both of the series of clutch teeth 154 and 155 are circularly arranged concentrically around the shaft 139 and may be any type of clutch or gear teeth well known in the art.

It should be noted that the righthand end of the shaft 139, minute-hand sleeve 140, and hour-hand sleeve 141 are all adapted to extend through a dial face of a clock and into a clock works of any suitable type. The dial face and the clock works are not shown, since they are well known in the art and various suitable types may be utilized with my invention.

The operation of the device may be described as follows. Knob 148 may assume a longitudinal shape, somewhat like a pointer, or any other suitable shape, and function as a seconds indicator cooperating with suitable indices arranged on the dial face. In the event that the time in seconds indicated by said seconds-indicating knob 148 is incorrect, it may be adjusted to the correct point by rotating same with respect to the shaft 139, since there is merely a frictional contact therebetween. After said adjustment, however, the seconds-indicating knob 148 will be driven by the seconds shaft 139, since the frictional contact therewith is sufficient to maintain a driving engagement without slippage.

The seconds-indicating knob 148 serves a dual purpose, since, as hereinbefore explained, it may be manually, axially shifted against action of the coil compression spring 150 with respect to the shaft 139 for engaging the clutch teeth 154 thereon and the clutch teeth 155 on the minute-hand hub 144 for adjusting the setting of the minute hand and hour hand which is customarily geared thereto.

It should be noted that while in the example shown the frontally extending means 148 passes through an aperture 156 in the clock crystal 157, this construction is optional and the frontally extending means may be positioned within the crystal and suitable means provided for removing the crystal for gaining access thereto, such as a hinged crystal mounting, or the like. It should also be noted that in the event the shaft 139 is not a seconds-indicating shaft and does not rotate, the knob 148 need not be of an indicating character and may simply provide a simple means for adjusting the minute and hour hands. It should also be noted that various other spring means may be utilized for retaining the frontally extending means 148 on the end of the shaft 139, the example illustrated being exemplary only.

Fig. 8 is a fragmentary partial vertical section similar to Fig. 7 of a modified, manual adjusting front setting means quite similar to that shown in Fig. 7. Similar elements are indicated by similar primed reference numerals.

The hour and minute hands 143' and 145' and the sleeves 141' and 140', shaft 139' and the clutch gear teeth 155' on the minute-hand hub or the end of the minute-hand sleeve are all exactly the same as similar elements shown in Fig. 7. However, the frontally extending, manual adjusting means 148' is slightly modified from that shown in Fig. 7, the hub portion 149' thereof being centrally bored in the same manner as the hub 149 in Fig. 7 with, however, no recess and straight locking spring, such as indicated at 152 and 151 in Fig. 7, and the annular groove 147 on the shaft 139 as shown in Fig. 7 is also dispensed with in the form of my invention shown in Fig. 8. The end of the shaft 139' is provided with a portion of reduced diameter indicated at 158, a shoulder 159 being provided at the rear end of said reduced portion 158 and being adapted to abut one end of a coil compression spring 150', the other end of which rests against the inner surface of the knob 148'. A screw 160 is screwed through the knob 148' and into the end of the reduced portion 158 of the shaft 139' for providing a stop for retaining the knob 148' on the shaft 139' for sliding or rotary movement with respect thereto.

The operation of the device is virtually the same as that described in connection with the

apparatus disclosed in Fig. 7; that is, the knob 148' may be rotated with respect to the shaft 139' for adjusting the seconds-indicating knob 148'. The knob 148' may also be pushed axially inwardly with respect to the shaft 139' against the action of the spring 150' for engaging the clutch gear teeth 154' on the inner end of the hub 149' and the clutch teeth 155' connected to the minute-hand hub 144' or the end of the minute-hand sleeve 140' for adjusting same while in said axially shifted position. The hour hand, being geared to the minute hand as is customary, will also be adjusted.

Fig. 9 is a fragmentary vertical section of a modified illustrative form of the manually adjustable, frontally extending front setting means of this invention. In this version of my invention the seconds-indicating adjusting knob 148'' is provided with a sliding, resilient, rearwardly extending sleeve portion 161 arranged to slide into and frictionally engage the inner surface of the end hole 146' in the outer end of the seconds shaft 139''. The balance of the elements are similar to those shown in Figs. 7 and 8 and similar reference numerals are utilized for indicating same.

The operation of the device may be described as follows. The seconds-indicating adjusting knob 148'' may be manually grasped and rotated with respect to the seconds-indicating shaft 139'' since only a frictional contact exists between the exterior surface of the sliding sleeve portion 161 and the interior surface of the end hole 146'. However, said frictional contact is sufficient to normally maintain a driving engagement with the seconds-indicating knob 148''. Other means may be provided for adjusting the minute and hour hands.

Numerous modifications and variations of this invention will occur to those skilled in the art and are intended to be comprehended and included in the scope of this invention, the examples herein being illustrative only of the principles of my invention. For example, the version of my invention illustrated in Fig. 6 might be modified so as to have more than two axial positions of the knob 107' whereby the pinion 115' may selectively engage more than two gears 118' and 132 for providing frontally extending, manual adjusting means for selectively adjusting either of two alarms or time-indicating hands. The engaging means for the various axial positions mentioned may comprise various types of gearing such as pinions and ordinary gears such as shown in Fig. 6, or may comprise end clutch gearing of the type shown in Fig. 5 and might be arranged whereby a completely extended position of the knob 107' engages one such end clutch gear and a complete pushed-in gearing position of the knob 107' would engage other similar clutch gearing and intermediate positions of any suitable number might engage various laterally arranged spur gears in separate parallel planes. Through various combinations of this basic idea a number of selective adjustments of various elements in a clock or other instrument may be made with one frontally extending setting means. The frontally extending means shown in Figs. 7 and 8 may be rotatably and slidably retained on the shaft by various other suitable means other than that shown herein and the frontally extending, adjustable seconds-indicating means shown in Fig. 8 may also engage the shaft in various ways whereby rotary adjustment therebetween may be effected. The type of clutch gearing such as shown in Figs. 7 and 8 may be modified within

wide limits. Under some circumstances it may be desirable to make it a uni-directional gearing.

The examples described and illustrated herein are exemplary only and are not intended to limit the scope of this invention, which is to be interpreted in the light of the appended claims only.

I claim:

1. In an electrically driven clock provided with a case, a clockwork mechanism within the case, a dial face, a clock crystal, and coaxially pivoted minute and hour hands between said face and crystal, the provision of: a rotatable seconds shaft operably associated with the clockwork mechanism; rotatable minute and hour sleeves supported on said seconds shaft in journaled relation; a forward extension on said seconds shaft projecting beyond the front ends of the minute and hour sleeves and into proximity with the clock crystal; a time setting means in front of the clock crystal and having a rearwardly extending hollow tubular portion sleeved over the forward extension of the seconds shaft and normally rotatable therewith for indicating seconds and adjustable thereon for resetting seconds; said tubular portion being slidably and axially movable on said extension to position said portion adjacent to said minute sleeve; and means carried by the tubular portion of the time setting means interengageable with means carried by the minute sleeve for instantly resetting time.
2. A device as claimed in claim 1 wherein the forward extension is provided with an annular groove and means are carried by the tubular portion of the time setting means for frictionally engaging the seconds shaft in said groove.
3. A device as recited in claim 1 wherein the means carried by the time setting means includes a spring means for biasing said time setting means out of engagement with the minute sleeve.
4. In an electrically driven clock provided with a case, clockwork mechanism within the case, a dial face, a clock crystal, and coaxially pivoted minute and hour hands between said face and crystal, the provision of: a rotatable second shaft operably associated with the clockwork mechanism; rotatable minute and hour sleeves supported on said seconds shaft in journaled relation; a forward extension on said seconds shaft projecting beyond the front ends of the minute and hour sleeves and into proximity with the clock crystal; a seconds indicator means in front of the crystal and having a rearwardly extending portion cooperatively engaged with the forward extension of the seconds shaft and guided thereby; said seconds indicator means being guidably movable in an axial direction along said forward extension; and means carried by the rearwardly extending portion interengageable with means carried by the minute sleeve whereby said minute hand may be set by rotation of said seconds indicator means.

5. In an electrically driven clock, provided with a case, a clock work mechanism within the case, a dial face, and coaxially pivoted minute and hour hands, the provision of: a rotatable seconds shaft within said clock work mechanism; hour and minute hand sleeves journaled on the shaft; and rotatably adjustable, second-indicating, frontally extending means slidably and frictionally carried by the shaft in front of the dial face adapted to operatively engage the minute-hand sleeve in response to axial movement of said frontally extending means with respect to said shaft and to translate manual rotation of said frontally extending means in said axially shifted position

into rotation of said minute-hand sleeve; clutch teeth provided on the forward end of the minute-hand sleeve, an annular recess in the forward end of the shaft and defined by a front and rear shoulder, said frontally extending means carried by said shaft comprising a manually actuatable knob, a rearwardly extending bored hub having a transverse recess in one wall thereof and an open rear end provided with clutch teeth adapted to selectively engage the clutch teeth on the minute-hand sleeve upon rearward axial movement of said hub, a retaining ball mounted in said transverse recess, a spring carried by said hub arranged to force the ball against the annular recess in the shaft for retaining the end thereof within the bored hub, and a coil compression spring positioned within said bored hub between the front thereof and the end of the shaft therein for normally spring biasing said hub forwardly until the retaining ball abuts the front shoulder of the annular recess whereby the clutch teeth carried by the minute-hand sleeve and the clutch teeth carried by the hub will normally be disengaged

but may be selectively engaged by manually, axially, rearwardly shifting the hub with respect to the shaft.

EDGAR BOURQUIN.
